PULL CHAIN AND WALL SWITCH

Howard Hallett, Wabasha, Minn.

Application November 5, 1934, Serial No. 751,653.

5 Claims. (Cl. 173—354)

The invention relates to switches, particularly of the pull chain socket type, but also of the wall type, for effecting the cutting off and on of an electric light.

5 Pull chain socket switches are of course familiar to everyone and it is well known that upon pulling the chain once the bulb is lit and that upon pulling it again the light is extinguished, switches of this character embodying ratchet 10 means operating always in the same direction but acting to make and break the circuit to the lamp upon successive steps of rotary movement of the actuating element.

The general object of the present invention is 15 to provide means forming part of or in association with such a switch which will delay the cutting off of the light when the chain is pulled to move the switch to the "off" position, the advantage being that after pulling the chain to extinguish the light the user will have a certain length of time in which he may leave the room or other place where the light is located and proceed to some other place without it being necessary to grope his way in darkness.

20 Broadly considered, the invention contemplates the provision of a novel dash-pot arrangement associated with the switch mechanism for the purpose of retarding or delaying the cutting off of the switch after the pull chain has been moved to the "off" position.

An important object of the invention is to provide a switch mechanism of this character which involves but comparatively little change from the conventional construction of devices of this general class.

25 An additional object is to provide a switch device having these characteristics and which will be simple and inexpensive to manufacture, easy to assemble, positive in action, efficient and durable in service, and a general improvement in the art.

To the attainment of the foregoing and other objects and advantages, the invention preferably 30 consists in the details of construction and the arrangement and combination of parts to be hereinafter more fully described and claimed, and illustrated in the accompanying drawings in which:

35 Figure 1 is a side elevation of a pull-chain type socket equipped with my mechanism,

Figure 2 is an elevation taken at right angles to Figure 1,

40 Figure 3 is a vertical section through the dash-pot taken on the line 3—3 of Figure 1,

Figure 4 is a cross section through the dash-pot taken on the line 4—4 of Figure 2,

Figure 5 is a detail longitudinal section through the chain guide and showing the dash-pot operating means,

Figure 6 is a side elevation of the mechanism within the socket, the latter being shown in section,

Figure 7 is a horizontal cross section taken on the line 7—7 of Figure 6,

Figure 8 is a cross section taken on the line 8—8 of Figure 6,

Figure 9 is a similar view taken on the line 9—9 of Figure 6,

Figure 10 is a detail perspective view showing 15 the stationary portion of the switch and the movable connecting member separated,

Figure 11 is a detail perspective view of the ratchet for operating the connecting member,

Figure 12 is a fragmentary detail view showing 20 the push-off means for causing the connecting member to move into circuit breaking position,

Figure 13 is a fragmentary detail view illustrating the push-off mechanism,

Figures 14 and 15 are views taken at right angles to each other and illustrating the adaptation of the invention to a wall type of switch.

Referring more particularly to the drawings and especially Figures 1 to 13 inclusive, the numeral 16 designates the shell of an electric light 30 socket of the pull chain type, this shell having the usual removable cap 17 and the shell and the cap having the customary lining 18 and 19 of insulating material. The cap has the usual bushed tubular sleeve portion 20 through which 35 are brought the current carrying wires which are connected interiorly of the shell and by means of the usual screws with upstanding metallic members 21 and 22, the former of which is connected with the threaded metal socket 23 depending from a porcelain or other dielectric base 24, and the latter of which is simply secured upon the top of this base. The upstanding metallic members 21 and 22 are secured to the underside of and carry a dielectric top member 25. All 40 this is in accordance with the usual construction of devices of this general class. At its center the base 24 has an upwardly projecting portion 26 which is stationary and of insulating material and which is formed with ratchet-tooth shaped 45 steps 27 and 28, the former of which are "dead" and the latter of which are "live" in that disposed thereon are stationary metallic contacts 29 one of which is connected with the metallic member 22 and the other of which is connected 50

with the central terminal, not shown, of the socket. In accordance with my invention the ends of the contacts 29 overhang the steps 27 and are downwardly offset to define ledges 30 and 5 abutment shoulders 31, as most clearly shown in Figure 10 and also as indicated in Figures 12 and 13.

Secured within the base 24 in coaxial relation thereto is an upstanding shaft or post 32 which has its upper end anchored within the top member 25. This post is stationary and rotatable thereon is a segmental shaped disk 33 carrying at its peripheral portion a channel shaped member 34 having one end formed with a U-shaped extension or outward projection 35 notched at 36 for engagement therein of the endmost bead 37 of a bead chain 38 of ordinary construction which lies within and is guided by the channel member 34 and which is brought out 10 through a tubular guide 39 located within an opening 40 in the shell 16. At one side, interiorly of the shell, this guide is formed with a stop lug 41 for limiting swinging movement of the actuating segment 33 in one direction when the chain 38 is pulled. Located beneath the segmental operating disk 33 is a ratchet disk 42 having upstanding tongues 43 engaged within notches 44 in the disk 33 and having their upper ends upset or pressed down so as to secure the ratchet 15 disk rigidly with respect to the actuating disk 33. This ratchet disk 42 has a plurality of stamped-out teeth 45 which are deflected downwardly as very clearly shown particularly in Figure 11.

Surrounding the post 32 is a coil spring 46 which abuts against the underside of the top member 25 and against the top of the actuating disk 33 for the purpose of urging the latter resiliently downwardly so that the ratchet disk 42 20 will cooperate properly with a connecting member shown in detail in Figure 10 formed as a disk 47 rotatable upon the post 32 and formed with radially extending teeth 48 engageable by the ratchet teeth 45 on the ratchet disk 42. This 25 disk 47 has diametrically extending arms 49 terminating in arcuate shoes 50 which are movable over the steps 27 and metallic contacts 29 on the steps 28 of the upward projection 26. It will be clear that when the shoes 50 are on the "dead" 30 steps 27 no current is supplied to the electric light bulb, not shown, which is screwed into the threaded socket 23, but that when the shoes 50 engage and bridge the contacts 29 on the steps 28 the circuit through such a lamp is completed. 35 It is the usual construction that when the chain of a switch of this character is pulled once the rotation of the actuating disk 33 and ratchet disk 42 carried thereby will cause the teeth 45 to engage the teeth 48 and turn the connecting member 47 a quarter turn. One quarter turn brings the shoes 50 into bridging relation to the contacts 29 and when the chain has been pulled to effect this and is let go the spring 46, which is a torsion spring as well as a compression spring 40 will return the disk 33 to its original position, the teeth 45 on the disk 42 then riding idly in ratchet fashion over the teeth 48 so that the position of the member 47 will be unchanged until the chain is again pulled to rotate the member 47 another 45 quarter turn to make the shoes 50 ride off from the contacts 29 onto the "dead" steps 27, whereupon the circuit to the lamp will be broken. This is the ordinary action. However, in my invention on account of the provision of the ledges 50 it will be seen that when the chain is pulled

to turn off the light the trailing ends of the members 50 will ride off from the contacts 29 onto the ledges 30 in view of the fact that the operating disk 33 will strike against the stop 41 and prevent the member 33 from moving a sufficient extent to cause the trailing ends of the members 50 to ride off from the ledges 30. It will therefore be seen that after the light has been turned on by one pull of the chain and the chain has been pulled a second time to extinguish the light, the 10 light will nevertheless remain energized as the connecting member 47 still bridges the contacts 29 owing to the engagement of the trailing ends of the members 50 on the ledges 30 in abutting relation to the shoulders 31. Advantage is taken 15 of this fact in the further carrying out of the invention.

In accordance with my new design of switch, I provide an arm 51 pivoted on a post 52 rising from the base 24 and urged into the path of 20 movement of the free end of the U-shaped member 35 of the channel 34 by means of a spring 53 extending through the post 52 and anchored to the arm 51. This arm 51 is mounted adjacent one of the ledges 30 as clearly indicated in Figures 25 7 and 13, the arrangement being such that when the chain is pulled to extinguish the light and is then let go the retrograde movement of the actuating disk 33 under the influence of the torsion spring 46, and of course the corresponding movement of the channel member 34 carried by the disk will cause the free end of the U-shaped member 35 at the end of the channel to engage against the outer end of the arm 51 and rock the arm upon its pivot 52 so that the inner end 35 of the arm will engage against the trailing end of the contact shoe 50 and force it off from the ledge 30 so that it may snap onto the "dead" steps 27, thereby breaking the circuit to the lamp as will be understood.

As pointed out in the objects, the principal feature of the invention is the provision of means for retarding or delaying the cutting off of the light. In order to accomplish this I provide in association with the other features described, a 45 dash-pot mechanism clearly shown in Figures 3 and 4 and comprising a cylinder 54 appropriately mounted on the side of the shell 16 of the socket, this cylinder containing an axially arranged shaft 55 journaled through a bearing 56 on the tubular chain guide 39. Within the dash-pot the shaft carries a ratchet 57 and a vane or blade 58 which is formed with a cylindrical portion 59 partially surrounding the ratchet but exposing a few teeth thereof with which cooperates a spring pawl 60 55 carried by the vane, the arrangement being such that the vane may move freely in one direction with respect to the shaft but must move with the shaft upon rotation thereof in the opposite direction. The dash-pot is intended to be filled 60 with oil which will of course pass through openings 61 in the vane and thereby permit the vane to turn but at slow speed. The shaft 55 carries a sprocket 62 which is located within a cut away portion 63 of the chain guide 39 and which is 65 engaged by the beads of the chain so that when the chain is pulled the sprocket and shaft 55 will be rotated.

It will be seen that in the operation when the chain is pulled in the usual manner to turn on 70 the light, the shaft 55 rotates freely with respect to the pawl 60 and vane 58 which consequently remains stationary. Pulling on the chain partially rotates the actuating disk 33 and channel 34 as well as the ratchet disk 42 and the teeth 45 75

of the latter cooperating with the teeth 48 of the connecting member 47 will rotate the member 47 a quarter turn and bring the contact shoes 50 from the "off" position on the "dead" steps 27 so that the shoes 50 will snap over onto the contacts 29, thereby completing the circuit to the lamp. When the chain is released the member 33 carrying the ratchet disk 42 returns under the influence of the spring 46 to its original position. 10 However, the movement is slow owing to the fact that the reverse rotation of the sprocket 62 and shaft 55 will cause the shaft to lock with the spring pawl 60 and cause rotation of the vane 58, rotation of which is impeded owing to the necessity of the oil flowing through the openings 61 as the vane turns. However, nothing else happens. 15 When it is desired to extinguish the light, the operator again pulls upon the chain, the shaft again riding idly under the spring pawl 60 so that the vane 58 and the spring 60 remain stationary. 20 This second pull upon the chain causes a partial rotation of the actuating disk 33 and ratchet disk 42 so that the teeth 45 of the latter cooperating with the teeth 48 will cause the connecting member 47 to have another quarter turn whereupon the shoes 50 will ride off from the major portions of the contacts 29 onto the ledges 30 where they will remain until the arm 51 is brought into play. 25 When the pull upon the chain is released, the torsion spring 42 tends to return the disk 33 to its original position but this movement is retarded owing to the fact that the reverse rotation of the sprocket 62 and shaft 55 will cause the ratchet 57 to lock with the pawl 60 so that the vane 58 30 will be rotated slowly as the oil within the dash-pot must pass through the openings 61. When the member 33 and channel 34 have almost reached the limit of the reverse movement, the free end of the U-shaped member 35 and the end 40 of the channel will engage against the outer end of the arm 51 and rock or partially rotate the same upon its pivot post 52 so that the inner end of this arm 51 will engage against the trailing end of one of the shoes 50 and move it off from the ledge 30 so that the connecting member 47 45 will be moved the necessary amount to cause the contact shoes 50 to spring down onto the "dead" steps 27. This delayed action of cutting off the switch will result in leaving the light energized for a certain length of time which will be sufficient for the user of the switch to leave the room where the light is located and make his way to some other room without it being necessary for him to grope about in darkness. 50

The invention is susceptible of employment in connection with or construction as a wall switch as indicated in Figures 14 and 15 and in such an instance the construction is identically the same except that the outer or free end of the pull chain is secured, as by a hook 64 to the sprocket. Moreover in this instance the shaft 55 carries a lever 65 projecting through a slot 66 in a face plate 67 secured to a wall. The mechanical construction in other respects is identically the same, the only difference being that there is no socket associated with the switch mechanism which is represented as supported between top and bottom dielectric members 68 and 69 corresponding to the above described members 25 and 24 respectively, these members 68 and 69 being either housed or mounted between supporting brackets 70 secured to the rear side of the face plate 67. The operation of this form is identically the same as above described except that instead of pulling 75 the chain to rotate the shaft 55 the shaft is ro-

tated by moving the lever 65 up or down as the case may be.

From the foregoing description and a study of the drawings it will be apparent that I have thus provided a simply constructed and consequently inexpensive switch device for the purpose specified and one which will efficiently perform all the functions for which it is intended. It will also be observed that the device differs from the ordinary type of switch only as regards the additional parts needed to carry out the specific operation desired, the mechanical construction in most respects following the common practice. It is believed that the construction, operation and advantages should be understood from the above without further explanation. 10 15

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended. 20 25

Having thus described the invention, I claim:

1. In an electric switch, a stationary ratchet structure of dielectric material, spaced contacts mounted on opposite sides of said stationary ratchet, a metallic connecting member rotatable with respect to said stationary ratchet and having shoes adapted to engage and bridge said contacts or to be disposed between the same in cut off position, teeth carried by said connecting member, a partially rotatable segmental actuating disk rotatable about the axis of said stationary ratchet, a ratchet disk carried by said actuating disk and cooperating with said teeth for rotating said connecting member step by step, a pull chain connected with said actuating disk, a dash-pot containing a fluid, a shaft journaled through said dash-pot and carrying a vane formed with openings for the passage of the fluid, a ratchet on said shaft within the dash-pot, a pawl on the vane cooperating with said last named ratchet for permitting relative rotation of the shaft and vane in one direction and for locking the vane for movement with the shaft in the opposite direction, and a sprocket on said shaft engaged by said chain to operate said shaft, said dash-pot and vane operating to delay return movement of the chain after it has been pulled. 50 55

2. In an electric switch, a stationary ratchet structure of dielectric material, spaced contacts mounted on opposite sides of said stationary ratchet, a metallic connecting member rotatable with respect to said stationary ratchet and having shoes adapted to engage and bridge said contacts or to be disposed between the same in cut off position, teeth carried by said connecting member, a partially rotatable segmental actuating disk rotatable about the axis of said stationary ratchet, a ratchet disk carried by said actuating disk and cooperating with said teeth for rotating said connecting member step by step, a pull chain connected with said actuating disk, a dash-pot containing a fluid, a shaft journaled through said dash-pot and carrying a vane formed with openings for the passage of the fluid, a ratchet on said shaft within the dash-pot, a pawl on the vane cooperating with said last named ratchet for permitting relative rotation 60 65 70 75 75

of the shaft and vane in one direction and for locking the vane for movement with the shaft in the opposite direction, a sprocket on said shaft engaged by said chain, said dash-pot and vane 5 operating to delay return movement of the chain after it has been pulled, said contacts having ledges on which said shoes rest when the chain is pulled to the "off" position, and means located in the path of return movement of said actuating 10 disk and engageable with said shoes for forcing the same off from said ledges to the "off" position when the actuating disk returns to normal position.

3. An electric switch comprising a stationary 15 ratchet of dielectric material, metallic contacts located upon opposite sides of the ratchet, a metallic connecting member rotatable about the axis of said stationary ratchet and having contact shoes adapted selectively to bridge said contacts or to be disposed between them, a segmental actuating disk rotatable about the axis of said stationary ratchet and connecting member and carrying ratchet means cooperating with said connecting member for partially rotating 20 the same step by step, combined compression and torsion spring means connected with said actuating disk for urging the same longitudinally toward the stationary ratchet and for resisting rotation thereof in one direction, downwardly offset ledges on said contacts, a pull chain 25 connected with said actuating disk for partially rotating the same and moving said connecting member step by step, a dash-pot operatively connected with said chain for delaying return movement thereof under the influence of 30 said spring subsequent to a pull upon the chain, said shoes being engageable upon said ledges when the chain is pulled to move the switch to the "off" position, and a pivoted spring-pressed lever located in the path of said actuating disk 35

upon return movement thereof to normal position engageable with one of said shoes for moving the connecting member off from both ledges into the "off" position.

4. In an electric switch embodying fixed and movable contacts and reciprocating actuating means operatively connected with the movable contact and requiring both a forward and return movement to disengage it from the fixed contact, the combination of a fluid containing 10 cylinder, a rotary vane mounted in said cylinder and retarded in its rotary movement by the fluid, a shaft supporting said vane and operatively connected with said reciprocating actuating means, and a pawl and ratchet connection 15 between the vane and said shaft so that the shaft may turn free of the vane in one direction of rotation but drives the vane when rotating in the other direction.

5. In an electric switch embodying fixed and 20 movable contacts and reciprocating actuating means operatively connected with the movable contact and requiring both a forward and return movement to disengage it from the fixed contact, the combination of a fluid containing 25 cylinder, a rotary vane mounted in said cylinder and retarded in its rotary movement by the fluid, a shaft supporting said vane and operatively connected with the said reciprocating actuating means, and a pawl and ratchet connection 30 between the vane and said shaft so that the shaft may turn free of the vane in one direction of rotation but drives the vane when rotating in the other direction, the said actuating means comprising a chain and the shaft carrying a sprocket over which the chain is trained and between the teeth of which the links of the chain engage.

HOWARD HALLETT. 40
